UNITED STATES PATENT OFFICE.

FRANKLIN H. CHILTON, OF NEW YORK, N. Y., ASSIGNOR TO CHARLES V. FAILE, OF SAME PLACE.

DRAWER-PULL.

SPECIFICATION forming part of Letters Patent No. 373,013, dated November 8, 1887.

Application filed June 1, 1887. Serial No. 239,934. (No model.)

To all whom it may concern:

Be it known that I, FRANKLIN H. CHILTON, a citizen of the United States, and a resident of New York, in the county of New York and 5 State of New York, have invented certain new and useful Improvements in Drawer-Pulls, of which the following is a specification.

The invention relates to improvements in drawer-pulls; and it consists of the elements 10 hereinafter described, and particularly pointed out in the claims.

The object of the invention, apart from cheapness and simplicity of construction, is to produce a drawer-pull adapted, when in 15 position, to present a smooth finished surface on the inner side of the drawer and a suitable head on the outer side of the drawer incapable of turning on its spindle and arranged to receive the drop-ring or handle.

20 In the accompanying drawings, forming a part of this application, Figure 1 is a longitudinal section of a drawer-pull embodying the invention, the section being on the line *x x* of Fig. 2, which is a sectional view on the line *Y Y* of Fig. 3. Fig. 3 is a sectional view on the line *Z Z* of Fig. 2. Fig. 4 is a view of the double-pointed tack hereinafter referred to. Fig. 5 is a transverse longitudinal section of a modified form of drawer-pull embodying 25 some of the features of the invention. Fig. 6 is an end view of the cylindrical spindle shown in Fig. 5, and Fig. 7 a view of the tack used therewith.

A in the drawings designates a flat plate 30 of appropriate length to pass almost entirely through the aperture B in the furniture, and having an enlarged shank end or head, C, the edges of which adjoining the main portion of the plate form laterally-projecting shoulders 35 D D. Upon the inner end of the plate A are formed, during the subsequent stages of the manufacture, the oppositely-projecting lips E E, hereinafter described, prior to the cutting of which the thimble F is passed upon 40 the head C from the inner end of the plate A, the end of the thimble being provided with a slot, G, to permit this movement, and the slot being of suitable width and length to snugly fit around the plate, the solid end of 45 the thimble adjacent to the ends of the slot being adapted to rest firmly against the shoul-

ders D D. After the thimble F has been passed over the head C from the point end of the plate A, the thimble H is passed upon the thimble F from (and closing) the open end 55 thereof, after which the apertures I J are cut through the opposite sides of said thimbles preparatory to receiving the opposite ends of the band K, constituting the drop-ring or handle. 60

The thimble F is prevented from turning on the head C by reason of the close-fitting slot G, and the thimble H is rendered incapable of revolving on the thimble F owing to its close fit and the fact that the ends of the band 65 K pass entirely through the apertures I J.

Within the end of the thimble H is dropped a metal disk, *a*, the purpose of which is merely to afford a double thickness of material at the outer end of the thimble, so as to avoid liability of the same being indented if accidentally struck. 70

In the inner end of the plate A are cut the oppositely-projecting lips E E, above referred to, one being on each side of the center of the 75 plate, and serving as guides for the points of the pins L L, connected with the head M, the whole forming what may be called for convenience a "double-pointed tack." After the plate A has been passed through the escutcheon N and aperture B, the pins L L are inserted into the aperture B from the inner side 80 of the piece of furniture, the pins being inclined toward each other and passing inward, one on each side of the plate A, until they 85 strike the lips E E, when they will be directed by said lips through the aperture O in the plate across the path of each other and into the opposite walls of the aperture B, thus securing the plate in position. The points of 90 the pins, prior to being inserted in the aperture B, may be bent toward each other, so as to facilitate their entrance through the aperture O in the plate and their passage across each other's path. The head M covers the 95 inner end of the aperture B and presents a finished surface, at the same time preventing any strain on the handle from withdrawing the plate A through the aperture B.

The modified form of the invention shown 100 in Fig. 5 will be readily understood. The tube P is substituted for the plate-spindle A, and

the points of the pins L are bent outward instead of inward, so as to be properly deflected by the inwardly-turned lips E cut from the tube.

5 What I claim as my invention, and desire to secure by Letters Patent, is—

1. In a drawer-pull, the plate A, having the head C and shoulders D, combined with the sheet-metal thimble F, having the slot G and side apertures I, the sheet-metal thimble H, having corresponding side apertures J, and the band K, the closed end of the inner thimble bearing against the shoulders D, and the closed end of the thimble H closing the outer or open end of the thimble F, substantially as set forth.

15 2. In a drawer-pull, the sheet-metal spindle having on its outer end a drop-handle and on

its inner portion the deflecting lips E E cut therefrom and leaving apertures therein, combined with the double-pointed tack consisting of the pins L L and head M, said pins being adapted to be deflected through the apertures in the spindle and into the wood by said lips, while the head of the tack closes the inner end of the aperture in the drawer, leaving a finished surface, substantially as set forth.

Signed at New York, in the county of New York and State of New York, this 26th day of 20 March, A. D. 1887.

FRANKLIN H. CHILTON.
